STENCILING APPARATUS

Herman N. Gordon, New York, N. Y.

Application July 9, 1947, Serial No. 759,865

11 Claims. (Cl. 101—123)

1

This invention relates to stencilling apparatus, especially of the silk-screen type, and more particularly to apparatus intended for ornamenting articles having a frustoconical surface.

The invention is here shown applied to the ornamentation of tableware or dishes. Although these are relatively flat, the ornamental border usually has a frustoconical surface. Heretofore, such tableware has been decorated either by hand, which, however, is very expensive, or has been decorated by decal transfer, which also is expensive because of the considerable time needed to apply the necessary pieces of decal transfer around the dish. A far better and faster way to ornament a ceramic surface is by the use of a silk screen. Such screens have heretofore been used on flat surfaces, and on cylindrical surfaces. It has also been proposed in the literature to use a silk screen of frustoconical form, which is rotated in rolling contact with a rotating dish, but so far as I am aware, this proposal has not proved successful.

The primary object of the present invention is to generally improve apparatus for ornamenting articles such as dishes, having a frustoconical surface. A more particular object is to provide a relatively simple and inexpensive form of apparatus, in which the dish remains stationary and the screen remains stationary in contact with the dish, it being necessary only to move a suitable squeegee over the surface of the screen.

Further objects are to facilitate the insertion and removal of the dish to be ornamented, and to facilitate the centering or registration of the screen relative to the dish when first setting up the apparatus for use with a new screen.

To accomplish the foregoing general objects, and other more specific objects which will hereinafter appear, my invention resides in the silk screen stencil elements and their relation one to the other, as are hereinafter more particularly described in the following specification. The specification is accompanied by drawings, in which:

Fig. 1 is a partially sectioned vertical section through apparatus embodying my invention;

Fig. 2 is a partially sectioned transverse elevation taken approximately in the plane of the line 2—2 of Fig. 1;

Fig. 3 is a fragmentary section drawn to enlarged scale, and taken approximately in the plane of the line 3—3 of Fig. 1;

Fig. 4 is a fragmentary section drawn to enlarged scale, and taken approximately in the plane of the line 4—4 of Fig. 1;

2

Fig. 5 is a view similar to Fig. 1, but taken through a modified form of the invention;

Fig. 6 is a similar view with the squeegees and presser in raised position;

Fig. 7 is a view similar to Fig. 5, but taken through still another modified form of the invention;

Fig. 8 is an end view of the squeegee shown in Fig. 7;

Fig. 9 is a perspective view of one form of hinge mechanism with adjusting screws for mounting the silk screen on the base; and

Figs. 10, 11 and 12 are explanatory of the vertical adjustment of the hinge mechanism.

Referring to the drawings, the invention is shown in three different forms. In all forms it comprises a base B having means thereon to locate the article or dish to be ornamented. There is a shaft S disposed over the base and

locating means, and a bearing in which the shaft is rotatably and axially movable. A yoke Y or equivalent support holds the bearing rigidly in position well above the base B. A suitable means, in this case a handle H, is provided to rotate the shaft. A silk screen A is carried by a frame F which is mounted on base B in proper position relative to the article to be ornamented, said frame being shaped to fit the frustoconical surface of the article. The mounting means M for the frame affords lifting of the screen, as shown in Fig. 2, for insertion of the article to be ornamented.

One or more squeegees G may be carried by the shaft S. The shaft is normally elevated, as by means of a spring C, but may be depressed to bring the squeegee in contact with the screen. Thus the complete arrangement makes it possible to place an article on the base B, to then lower the screen frame F to bring the screen in position on the article, and to thereupon lower the shaft and squeegees for rotation

over the screen.

Considering the arrangement in greater detail, and referring first to the form of the invention shown in Figs. 1 through 4, the frame F comprises a peripheral portion 12 and a central portion 14 connected by a diametrical cross-bar 16. The central portion 14 has a bottom surface which is lower than the peripheral portion 12, so that the annular portion 18 of the screen exposed between the peripheral and central portions, is held in frustoconical shape. There are two squeegee holders 20 and 22 mounted on a bar 24 carried at the lower end of shaft 26 so that the squeegees are approximately 180° apart, and are arranged for simultaneous movement

45

50

55

over annular screen A. Thus rotation of the shaft for approximately 180° causes the two squeegees to travel over substantially the entire periphery of the screen.

Because of the cross-bar 16, the arrangement as so far described would not provide for full coverage. The arrangement would nevertheless be useful for interrupted designs, for the cross-bar would be located between parts of the design. However, in accordance with a further and more detailed feature of the invention, the cross-bar 16 and the upright squeegee supports 20 and 22 may be so relatively shaped and located on opposite sides of the screen, that the squeegees may be revolved a full 180° despite the presence of the cross-bar. In the specific arrangement here shown, the radial portion 28 of the cross-bar is bent downwardly or disposed at a lower elevation, while the opposite radial portion 30 of the cross-bar is disposed at a higher elevation. The squeegee support 20 is bent or channeled at 32 to clear the lower portion 28 of the cross-bar, while the support 22 is bent or channeled in opposite direction at 34 to clear the higher portion of the cross-bar. The relation of the channel or bend 32 to the cross-bar 28 is best shown in Fig. 3, while the relation of the channel or bend 34 to the cross-bar 30, is best shown in Fig. 4.

In Fig. 3 the height of the higher portion 30 of the cross-bar is shown in dotted lines at 30', and it will be observed that the bend or channel 32 clears the higher as well as the lower portions of the cross-bar. In Fig. 4, much the same remark applies to the dotted showing 28' of the lower portion of the cross-bar, for the bend or channel 34 of the squeegee holder 22 clears the part 28' as well as the part 30. On reflection, it will be seen that with this arrangement the shaft 26 may be turned a full 180°, and in fact, a little more, thus causing the working edges 36 of the rubber squeegees 38 to travel over the entire surface of the screen. The arrangement therefore may be used with a continuous design.

The dish 40 is properly located on base B by means of a locating disc or pilot 42. This is held on the base by means of a suitable screw 44. The pilot disc is readily removable and replaceable when changing from the ornamentation of one size or type of dish to another. For each size of dish, a pilot disc is made up of suitable diameter to properly fit the dish.

The screen frame F is preferably circular on the inside, to conform to the circular dish, but the frame may be and preferably is square on the outside. This facilitates mounting and handling of the screen.

A different screen is provided for each type of dish. It is evident that the frame is designed to fit the dish, hence different frames are needed for dishes of different size. Moreover, dishes having the same size but different patterns, require a different screen or stencil, and it is preferred that the screen be mounted on the frame and left with the frame so that it is available for use when wanted.

The squeegee holders 20 and 22 may be adjustably mounted on the cross-bar 24. In the present case the cross-bar is slotted at 46 so that the radius at which the squeegees are revolved may be varied. The squeegee is secured to the cross-bar by means of screws 48. In this particular arrangement no provision is made for changing the angle of the squeegees because of the channels 32 and 34. However, in a simpler

arrangement not required to rotate a full 180°, the channels 32 and 34 may be omitted, and in such case the squeegee may be arranged for adjustment of angle, as is described later in connection with other species of the invention.

The spring C is housed within a hollow bearing 50. The top portion 52 acts as an upper bearing, while a removable plate acts as a lower bearing. The lower end of spring C rests on plate 54, while the upper end bears against a collar 56 secured to the shaft S. It will thus be evident that the spring tends normally to raise the shaft from the position shown in Fig. 1 to the position shown in Fig. 2. This in turn raises the squeegees and so provides clearance for elevation of the screen frame, as shown in Fig. 2.

The frame may be arranged to be raised bodily, but I prefer to hinge the same, as shown in Fig. 2, the hinge pin being indicated at 60. The base is provided with releasable lock means indicated at 62, and to release the screen, the lock means is moved from the dotted-line position 62' to the solid-line position 62, whereupon the screen may be raised from the broken-line position F' to the solid-line position F.

The hinge means is preferably provided with appropriate screw adjustments for varying the position of the frame on the base or relative to the locating means, in order to properly register the ornamentation on the dish when first setting up a new screen. For this purpose, the hinge mechanism is preferably provided with a plurality of screw adjustments for varying the position of the frame in different directions. One arrangement for the purpose is shown in Figs. 9 through 12 of the drawings. In this arrangement the frame F (Fig. 10) has a plate 64 secured to it by means of screws, said plate including a track or guide 66. The hinge bearing 68 is formed on the lower end of a channeled member 70 which is vertically slidable on the guide 66. A wing screw 72 is threadedly received in the plate 64, and passes through a slot 74 in member 70. With this arrangement, it will be evident that the height of the frame or its distance away from the base, may be varied. Such a change is indicated in Fig. 10, by the spacing between the solid-line position 68 and the broken-line position 68' of the hinge.

It will be understood that there are two such hinge bearings 68 suitably spaced apart on the outer edge of the frame. These hinge bearings are received between mating hinge bearings 76, best shown in Fig. 9, the said bearings being formed on a plate 78 which may be moved axially of the hinge by means of screws 80 having enlarged knurled heads 82. By turning one screw in a loosening direction and the other in a tightening direction, the plate 78 may be moved in one direction or the other.

The plate 78 may also be moved in a transverse direction by means of screws 84 received in mating threaded parts 86 of the plate 78. There are mating screws extending in opposite directions, so that one screw may be loosened while the other is tightened, as previously described, but in this case the screws pass through plates 88 which are movable in the direction of the axis of the hinge along with the plate 78. At the same time the ends of the screws 80 are received in plates 90 which are moved transversely of the axis of the hinge along with the plate 78. It will be evident that altogether, adjustment in three mutually perpendicular directions has been provided.

A modification of the invention is shown in Figs. 5 and 6 of the drawing. In this arrangement, the yoke Y carries shaft S and handle H, just as previously described. The shaft is normally urged upwardly by spring C, and is provided at its upper end with a knob 92 which facilitates depressing the shaft from the position shown in Fig. 6 to the position shown in Fig. 5, just as was previously described. The shaft carries a cross-bar 94 with squeegees 96, and in this case the squeegees may be angularly adjusted, as by means of the arcuate slots 98.

In the present case, one important change is in the stencil frame F, for the central portion 100 is not connected to the peripheral portion 102 by means of a cross-bar. Instead, it is connected solely by means of the silk screen A. However, the central portion 100 is pressed firmly against the dish before the stencilling operation is begun, this being accomplished by a presser 104 yieldably mounted at the lower end of shaft S. The presser is normally urged downwardly by means of a suitable compression spring 106, and the dimensioning of the parts is such that when the shaft is pushed downwardly by means of knob 96, the presser bears against the central portion 100 of the screen before the squeegees reach the screen.

From a structural standpoint, the central portion of the screen might be omitted, and the presser 104 could be made of appropriate diameter to properly shape the screen before the stencilling operation begins. However, it is preferred to provide the central portion 100 not only with a view to permitting the presser 104 to be universally applicable to a large number of different screens, but even more important, to confine the heavy, ceramic paint, which is distributed on the screen, to the exposed annular portion of the screen, instead of permitting it to run down to the middle of the screen where in no case could it be usefully employed.

The hinge mounting and releasable lock for the frame need not be described in detail, for they may be identical with those described for use in connection with the first form of the invention.

Still another form of the invention is shown in Figs. 7 and 8. This will have far less application than the modifications previously described, for in the present case the arrangement is intended solely to ornament the flat central portion of the dish. However, the dish has a frustoconical outer portion which would prevent the screen from being placed flat over the dish. Instead, a frame F is provided which is frustoconically shaped on its lower surface 110 to conform to the dish. The screen is stretched across the frame for use at the center of the dish, and the squeegee 112 may be mounted diametrically on the shaft 114. It will be understood that there is a handle and presser knob at the top of the shaft, although not shown in Fig. 7, and that a spring is located within the bearing 116, all as previously described.

It is believed that the construction and operation of the improved apparatus of my invention, as well as the advantages thereof, will be apparent from the foregoing detailed description. It will also be apparent that while I have shown and described the invention in several preferred forms, many changes may be made in the structures disclosed, without departing from the spirit of the invention as sought to be defined in the following claims.

1. **Claim:**

1. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, said frame being shaped to give said frame and screen combination a frusto conical shape such as to fit the frusto conical surface of the article, and a squeegee carried by said shaft, the arrangement being such that an article may be placed on the base, the frusto conical screen lowered into mating contact therewith, the shaft and squeegee lowered into contact with the screen, and said shaft rotated relative to the non-rotatable article and screen in order to move the squeegee over the screen and thereby ornament the article, the frame having a peripheral portion hingedly mounted on the base at one side and provided with releasable lock means on the other side to hold the frame downward against the article to be ornamented, said hinge means including a screw adjustment for varying the position of the frame relative to the locating means.

2. Silk screen stencilling apparatus for ornamenting an article having a frusto conical surface,

3. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, said frame being shaped to give said frame and screen combination a frusto conical shape such as to fit the frusto conical surface of the article, and a squeegee carried by said shaft, the arrangement being such that an article may be placed on the base, the frusto conical screen lowered into mating contact therewith, the shaft and squeegee lowered into contact with the screen, and said shaft rotated relative to the non-rotatable article and screen in order to move the squeegee over the screen and thereby ornament the article, the frame having a peripheral portion hingedly mounted on the base at one side and provided with releasable lock means on the other side to hold the frame downward against the article to be ornamented, said hinge means including a plurality of screw adjustments for varying the position of the frame in different directions relative to the locating means.

4. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried

by a frame, mounting means mounting said frame on said base in proper position relative to the article to be ornamented, the mounting means for said frame affording lifting of the screen for insertion of an article to be ornamented, said frame being shaped to give said frame and screen combination a frusto conical shape such as to fit the frusto conical surface of the article, and a squeegee carried by said shaft, the arrangement being such that an article may be placed on the base, the frusto conical screen lowered into mating contact therewith, the shaft and squeegee lowered into contact with the screen, and said shaft rotated relative to the non-rotatable article and screen in order to move the squeegee over the screen and thereby ornament the article, the frame having a peripheral portion hingedly mounted on the base at one side and provided with releasable lock means on the other side to hold the frame downward against the article to be ornamented, said hinge means including a screw adjustment for varying the position of the frame relative to the locating means in one direction, screw means for varying the position of the frame relative to the locating means in transverse direction, screw means for varying the position of the frame in a direction toward or away from the base, and said lock means being adjustable toward or away from the base.

4. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, the frame comprising a peripheral portion and a central portion, said central portion having a bottom surface designed to be disposed lower than the peripheral portion, whereby the annular portion of the screen exposed between the peripheral and central portions may be held in frusto conical shape to fit the frusto conical surface of the article, and a squeegee carried by said shaft, the arrangement being such that an article may be placed on the base, the frusto conical screen lowered into mating contact therewith, the shaft and squeegee lowered into contact with the screen, and said shaft rotated relative to the non-rotatable article and screen in order to move the squeegee over the screen and thereby ornament the article, and the lower end of the shaft being provided with a presser, means associated with said shaft and presser whereby the presser is resiliently urged downwardly relative to the shaft, whereby downward movement of the shaft brings the presser into contact with the central portion of the frame of the screen to press the same against the article before the squeegee comes into contact with the screen.

5. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft

for a substantial distance, a silk screen carried by a frame, mounting means mounting said frame on said base in proper position relative to the article to be ornamented, the mounting means for said frame affording lifting of the screen for insertion of an article to be ornamented, the frame comprising a peripheral portion and a central portion, said central portion having a bottom surface designed to be lower than the peripheral portion, whereby the annular portion of the screen exposed between the peripheral and central portions may be held in frusto conical shape to fit the frusto conical surface of the article, and squeegees carried by said shaft, the arrangement being such that an article may be placed on the base, the frusto conical screen lowered into mating contact therewith, the shaft and squeegees lowered into contact with the screen, and said shaft rotated relative to the non-rotatable article and screen in order to move the squeegees over the screen and thereby ornament the article, there being two squeegees mounted on opposite sides of said shaft approximately 180° apart for simultaneous cooperation with the frusto conical portion of the screen, and the lower end of the shaft being provided with a presser, means associated with said shaft and presser whereby the presser is resiliently urged downwardly relative to the shaft, whereby downward movement of the shaft brings the presser into contact with the central portion of the frame of the screen to press the same against the article before the squeegees come into contact with the screen.

6. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, the frame comprising a peripheral portion and a central portion connected by a diametrical cross-bar, said central portion having a bottom surface lower than the peripheral portion, whereby the annular portion of the screen exposed between the peripheral and central portions is held in frusto conical shape to fit the frusto conical surface of the article, and squeegees carried by said shaft, the arrangement being such that an article may be placed on the base, the frusto conical screen lowered into mating contact therewith, the shaft and squeegees lowered into contact with the screen, and said shaft rotated relative to the non-rotatable article and screen in order to move the squeegees over the screen and thereby ornament the article, there being two squeegees mounted on opposite sides of said shaft approximately 180° apart for simultaneous movement over the frusto conical portion of the screen, whereby rotation of said shaft for approximately 180° causes the two squeegees to travel over substantially the entire periphery of the exposed annular portion of the screen, the squeegees including upright portions extending to a point above the cross-bar for attachment to the shaft, said upright portions and said cross-bar being so relatively shaped and located at diametrically opposite

parts of the screen that the squeegees may be revolved a full 180° despite the presence of the cross-bar.

7. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, the frame comprising a peripheral portion and a central portion connected by a diametrical cross-bar, said central portion having a bottom surface lower than the peripheral portion, whereby the annular portion of the screen exposed between the peripheral and central portions is held in frusto conical shape to fit the frusto conical surface of the article, and squeegees carried by said shaft, the arrangement being such that an article may be placed on the base, the frusto conical screen lowered into mating contact therewith, the shaft and squeegees lowered into contact with the screen, and said shaft rotated relative to the non-rotatable article and screen in order to move the squeegees over the screen and thereby ornament the article, there being two squeegees mounted on opposite sides of said shaft approximately 180° apart for simultaneous movement over the frusto conical portion of the screen, whereby rotation of said shaft for approximately 180° causes the two squeegees to travel over substantially the entire periphery of the exposed annular portion of the screen, the cross-bar being disposed at one elevation on one side of the screen and at a different elevation at the other side of the screen, and the squeegees including upright portions extending to a point above the cross-bar for attachment to the shaft, one of said upright portions being bent or channeled in one direction to clear the lower part of the cross-bar, and the other of said upright portions being bent or channeled in opposite direction to clear the higher part of the cross-bar, the lower bend or channel also clearing the higher cross-bar, and the higher bend or channel also clearing the lower cross-bar, whereby the squeegees may be revolved a full 180° despite the presence of the cross-bar, the peripheral portion of the frame being hingedly mounted on the base at one side, and being provided with releasable lock means on the other side to hold the frame downward against the article to be ornamented.

8. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, the frame comprising a peripheral portion and a central portion connected by a diametrical cross-bar, said central portion having a bottom surface lower than the peripheral portion, whereby the annular portion of the screen

exposed between the peripheral and central portions is held in frusto conical shape to fit the frusto conical surface of the article, and squeegees carried by said shaft, the arrangement being such that an article may be placed on the base, the frusto conical screen lowered into mating contact therewith, the shaft and squeegees lowered into contact with the screen, and said shaft rotated relative to the non-rotatable article and screen in order to move the squeegees over the screen and thereby ornament the article, there being two squeegees mounted on opposite sides of said shaft approximately 180° apart for simultaneous movement over the frusto conical portion of the screen, whereby rotation of said shaft for approximately 180° causes the two squeegees to travel over substantially the entire periphery of the exposed annular portion of the screen, the cross-bar being disposed at one elevation on one side of the screen and at a different elevation at the other side of the screen, and the squeegees including upright portions extending to a point above the cross-bar for attachment to the shaft, one of said upright portions being bent or channeled in one direction to clear the lower part of the cross-bar, and the other of said upright portions being bent or channeled in opposite direction to clear the higher part of the cross-bar, the lower bend or channel also clearing the higher cross-bar, and the higher bend or channel also clearing the lower cross-bar, whereby the squeegees may be revolved a full 180° despite the presence of the cross-bar, the peripheral portion of the frame being hingedly mounted on the base at one side, and being provided with releasable lock means on the other side to hold the frame downward against the article to be ornamented.

9. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, the frame comprising a peripheral portion and a central portion connected by a diametrical cross-bar, said central portion having a bottom surface lower than the peripheral portion, whereby the annular portion of the screen exposed between the peripheral and central portions is held in frusto conical shape to fit the frusto conical surface of the article, and squeegees carried by said shaft, the arrangement being such that an article may be placed on the base, the frusto conical screen lowered into mating contact therewith, the shaft and squeegees lowered into contact with the screen, and said shaft rotated relative to the non-rotatable article and screen in order to move the squeegees over the screen and thereby ornament the article, there being two squeegees mounted on opposite sides of said shaft approximately 180° apart for simultaneous movement over the frusto conical portion of the screen, whereby rotation of said shaft for approximately 180° causes the two squeegees to travel over substantially the entire periphery of the exposed annular portion

11

of the screen, the cross-bar being disposed at one elevation on one side of the screen and at a different elevation at the other side of the screen, and the squeegees including upright portions extending to a point above the cross-bar for attachment to the shaft, one of said upright portions being bent or channeled in one direction to clear the lower part of the cross-bar, and the other of said upright portions being bent or channeled in opposite direction to clear the higher part of the cross-bar, the lower bend or channel also clearing the higher cross-bar, and the higher bend or channel also clearing the lower cross-bar, whereby the squeegees may be revolved a full 180° despite the presence of the cross-bar, the peripheral portion of the frame being hingedly mounted on the base at one side, and being provided with releasable lock means on the other side to hold the frame downward against the article to be ornamented, said hinge means including a screw adjustment for varying the position of the frame relative to the locating means in one direction, screw means for varying the position of the frame relative to the locating means in transverse direction, screw means for varying the position of the frame in a direction toward or away from the base, and said lock means being adjustable toward or away from the base.

10. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, the frame comprising a peripheral portion shaped to conform to the frusto conical article, the screen being stretched across said frame for use at the center of the article, and a squeegee carried by said shaft, the arrangement being

such that an article may be placed on the base, the frusto conical screen lowered into mating contact therewith, the shaft and squeegee lowered into contact with the screen, and said shaft rotated relative to the non-rotatable article and screen in order to move the squeegee over the screen and thereby ornament the article.

11. Silk screen stencilling apparatus for ornamenting an article having a frusto conical surface, said apparatus being adapted for bench or table top mounting and comprising a flat base having stationary means thereon to locate the article, a shaft disposed over said locating means, bearing means so supporting said shaft as to afford rotation of the shaft and lifting of the shaft for a substantial distance, a silk screen carried by a frame, mounting means mounting said frame on said base in proper position relative to the article to be ornamented, the mounting means for said frame affording lifting of the screen for insertion of an article to be ornamented, the frame comprising a peripheral portion shaped to conform to the frusto conical article, and the screen being stretched across said frame for use at the center of the article, and a squeegee carried by said shaft, said squeegee being disposed diametrically of the shaft for cooperation with the exposed central portion of the screen, the arrangement being such that an article may be placed on the base, the frusto conical screen lowered into mating contact therewith, the shaft and squeegee lowered into contact with the screen, and said shaft rotated relative to the non-rotatable article and screen in order to move the squeegee over the screen and thereby ornament the article.
